UNITED STATES PATENT OFFICE.

WILLIAM F. NORMAN, OF NEVADA, MISSOURI.

METAL BINDER.

1,052,617.

Specification of Letters Patent. Patented Feb. 11, 1913.

Application filed May 20, 1912. Serial No. 698,659.

To all whom it may concern:

Be it known that I, WILLIAM F. NORMAN, a citizen of the United States, residing at Nevada city, in the county of Vernon and 5 State of Missouri, have invented a new and useful Metal Binder, of which the following is a specification.

The present invention aims to provide a 10 novel form of binder for the edges of carpets, rugs and the like, novel means being provided for holding the arms of the binder together, and for retaining the carpet, rug or other article between the arms.

With the foregoing and other objects in 15 view, which will appear as the description proceeds, the invention resides in the combination and arrangement of parts and in the details of construction hereinafter described and claimed, it being understood 20 that changes in the precise embodiment of the invention herein disclosed can be made within the scope of what is claimed without departing from the spirit of the invention.

In the drawings,—Figure 1 shows in perspective, a rug or the like, to the edge of which, a binder constructed in accordance with the present invention, has been applied; Fig. 2 is a perspective of the binder, opened to receive the rug; Fig. 3 is a transverse section of the structure shown in Fig. 2; Fig. 4 is a transverse section of the structure shown in Fig. 1; Fig. 5 is a transverse section disclosing a modified form of the invention, the binder being partially applied to the rug; and Fig. 6 is a transverse section of the structure shown in Fig. 5, the operation of applying the binder having been completed.

Referring to Figs. 1, 2, 3 and 4, the binder 40 is shown as fashioned from an arched strip of flexible metal, denoted by the numeral 1, the binder comprising connected arms. One arm of the binder comprises a body 2 and a reversely curved flange 3. The other arm of the binder comprises a body 4 and a reversely curved flange 6. In some portion of one arm of the binder, and preferably in the flange 3, there is fashioned an opening 7. Projecting from the other arm of the binder, 45 and ordinarily from the flange 6, is a tongue 50

8 which may be struck from the flange, the tongue, if desired, terminating in a pointed prong 9.

When the parts are positioned as shown in Fig. 2, the rug 10 is introduced between 55 the arms, and the body portions 2 and 4 of the arms are closed together, whereupon the tongue 8 will be thrust through the rug 10, the tongue entering the opening 7 and ultimately becoming engaged between the flange 60 3 and the body 2, as disclosed in Fig. 4, the body 2 constituting means for deflecting the tongue 8 laterally. The flanges 3 and 6 are disposed between the body portions 2 and 4 of the arms, and in fashioning the flanges 65 3 and 6, the binder is rounded at its edges, as shown at 11, to prevent a cutting of the rug 10.

In Figs. 5 and 6, a modified form of the invention is shown. The strip 12 comprises 70 connected arms, one arm comprising, as constituent elements, a body 14 and a flange 15 which may be equipped with a back-bent lip 16. The other arm of the binder comprises as constituent elements, a body 17 and 75 a flange 18. In some portion of one arm, and preferably in the body portion 14 thereof there is fashioned an opening 19, the other arm being equipped with a tongue 20 which may be struck from the flange 18. 80 The flange 18 lies between the body portions 14 and 17 of the arms, the flange 15 lying upon the outside of the body portion 14 of one arm.

In practical operation, the rug 21 is inserted 85 between the body portions 14 and 17 of the arms, and the body portions are crowded together, as shown in Fig. 5, so as to force the tongue 20 through the rug 21 and through the opening 19 in the arm 14. The 90 flange 15 is then bent over upon the tongue 20, the tongue being bound between the flange 15 and the body 14, as shown in Fig. 6.

Having thus described the invention, what 95 is claimed is:—

A binder of the class described comprising connected arms, each arm comprising as constituent elements, a body and a reversely curved flange, one of said constituent ele- 100

ments of one arm being provided with an opening, there being a tongue projecting from the flange of the other arm and adapted to pass through the opening, and to be bound between the body and the flange of that arm which is provided with the opening.

In testimony that I claim the foregoing as my own, I have hereto affixed my signature in the presence of two witnesses.

WILLIAM F. NORMAN.
